Inventor:

E. N. Corbett.

UNITED STATES PATENT OFFICE.

E. M. CORBETT, OF NEW YORK, N. Y.

CAMERA-STAND.

Specification forming part of Letters Patent No. 35,671, dated June 24, 1862.

To all whom it may concern:

Be it known that I, E. M. CORBETT, of the city, county, and State of New York, have invented a new and Improved Camera-Stand; and I do hereby declare that the following is a full, clear, and exact description of the same, reference being had to the accompanying drawings, forming a part of this specification, in which—

Figure 1 represents a longitudinal vertical section of my invention, the line xx , Fig. 2, indicating the plane of section. Fig. 2 is a rear elevation of the same.

Similar letters of reference in both views indicate corresponding parts.

This invention consists in the arrangement of two diagonal frames connected together on the principle of lazy-tongs and hinged at their opposite ends to the rising and falling platform, which supports the camera, and to the stationary top of the stand, in combination with slides which permit said diagonal frames to adjust themselves according to their higher or lower position in such a manner that the platform, with the camera, can be raised or lowered in parallel planes, and that the same is supported perfectly firm and steady in front and rear in whatever position it may be brought.

It consists, also, in the employment or use of a wedge-shaped hinged slide moving in grooves in the sides of the platform for the purpose of adjusting the inclination of the camera.

To enable those skilled in the art to make and use my invention, I will proceed to describe it with reference to the drawings.

The stand A consists of the movable platform B, the stationary top C, and three legs, D.

The platform B is connected with the stationary top C by means of the frames E E', which are secured together in their centers by pivots *a*, on the principle of lazy-tongs. The frame E is attached with one end, by means of hinges *b*, to the edge of the stationary top C, and with its other end, by means of hinges *c*, to the opposite edge of the platform B, and the frame E' connects, by means of hinges *d e*, with slides *f g*, the slides *f* being retained by grooved guides *f'*, that are secured

to the under side of the platform near to its front edge, and the slides *g* by similar grooved guides, *g'*, that are attached to stationary top C near its rear edge, as clearly shown in Fig. 1 of the drawings. A hand-lever, F, which is hinged to the under side of the stationary top C, connects, by a bar or frame, G, with one of the diagonal frames, E', said connecting-frame being attached to the lever F by a pivot or pivots, *h*, and to the diagonal frame E' by pivots *i*, so that by raising or depressing the lever the platform B can be adjusted higher or lower, as may be desired, and in whatever position the platform may be brought it is always firmly supported on four pivots, so that it affords a firm support for the camera, and that the danger of spoiling the pictures by a shake of the camera-stand is avoided, or at least considerably lessened.

The lever F passes through a slot, *j*, in the front leg, and it may be secured in the desired position by a screw-bolt, *k*, moving in slots *l m* in the lever and leg, or by any other desirable means; and by fastening the lever the platform is also secured in the position in which it has been brought by the action of said lever. It must be remarked, however, that the platform might be secured by any other desirable means with equal advantage—such as spring-catches *k'* catching into the serrated edges of the frame G.

Two flanges, *n*, project over the side edges of the platform, and these flanges are provided with grooves *o* to form the guides for a wedge-shaped hinged slide, H. By pushing this slide more or less under the rear edge of the camera the inclination of the latter toward the horizon can be adjusted at pleasure.

If it is desired to place the camera flat down on the platform B, the slide H is drawn back until the hinged part turns down beyond the edge of the platform, and that portion of the hinged slide which remains in the grooves *o* forms a stop to prevent the camera falling off by accident, and at the same time the slide is always in its place and is not liable to get lost.

Having thus fully described my invention, what I claim as new, and desire to secure by Letters Patent, is—

1. The arrangement of the diagonal frames

E E', connected together by pivots *a*, on the principle of lazy-tongs, in combination with slides *f g*, and with the movable platform B and stationary top C, the latter being supported by three legs, D, substantially in the manner and for the purpose shown and described.

2. The employment of the wedge-shaped

hinged slide H, guided by grooves *o* in the side flanges, *n*, of the platform B, as and for the purpose specified.

E. M. CORBETT.
